DESIGN FOR A HOOD FOR BOTTLE WASHING MACHINES

Jesse W. Fogg, Barrington, Ill., and Fred H. Fruhling, Little Falls, N. Y., assignors to Cherry-Burrell Corporation, Wilmington, Del., a corporation

Application April 12, 1937, Serial No. 68,700

Term of patent 14 years

To all whom it may concern:

Be it known that we, Jesse W. Fogg and Fred H. Fruhling, citizens of the United States, residing at Barrington, in the county of Cook, State of Illinois, and at Little Falls, in the county of Herkimer and State of New York, respectively, have invented a new, original, and ornamental Design for Hood for Bottle Washing Machines, of which the following is a specification, reference being had to the accompanying drawing, forming part thereof.

Figure 1 shows a perspective view of a hood for bottle washing machines showing our new design.

Figure 2 is a side elevation of same; and

Figure 3 is a side elevation of same showing the opposite side.

We claim:

The ornamental design for a hood for bottle washing machines, substantially as shown.
